UNITED STATES PATENT OFFICE.

DOUGLAS M. CAREY, OF ENID, OKLAHOMA TERRITORY.

TRAM FOR ROLLER GRINDING-MILLS.

SPECIFICATION forming part of Letters Patent No. 635,528, dated October 24, 1899.

Application filed March 24, 1899. Serial No. 710,288. (No model.)

To all whom it may concern:

Be it known that I, DOUGLAS M. CAREY, a citizen of the United States, residing at Enid, in the county of Garfield and Territory of Oklahoma, have invented certain new and useful Improvements in Trams for Roller Grinding-Mills, of which the following is a specification, reference being had therein to the accompanying drawings.

10 This invention has relation to means for adjusting the leveling-rollers in grinding-mills and like machinery; and it consists in the novel construction and combination and arrangement of parts of which it is composed, 15 all as will be hereinafter fully explained, and particularly pointed out in the appended claims.

The annexed drawings, to which reference is made, fully illustrate my invention, in 20 which—

Figure 1 represents an edge view of my device applied to a pair of grinding-rollers. Fig. 2 is a plan view of the same detached from the rollers. Fig. 3 is a vertical sectional view 25 of the same, and Fig. 4 is a detailed view showing one of the adjustable plates.

Referring by letter to the accompanying drawings, A designates a wheel, or disk may be employed instead, which is provided with 30 a central perforation a, through which is loosely passed the stem b of a handle c, and which stem serves as a journal or axle, on which said wheel revolves horizontally.

B designates a flat bar which is bent downwardly at right angles to the main portion and is provided with a central female-threaded opening d, in which is screwed the end e of the stem aforesaid, thus interposing the wheel A between the shoulder f of the handle 40 and the bar B. The bent ends of the bar are perforated, and are provided with thumb-screws g g, which engage in horizontally-arranged slots h in a pair of plates i i. The ends j j are curved to correspond with and engage the surfaces of the adjacent rollers, as 45 shown in Fig. 1 of the drawings.

It will thus be observed from the above description, when taken in connection with the drawings, that my device is portable and can 50 be moved from one set of rollers to another, and in testing, gaging, or leveling the rollers the device is laid upon the upper surface of

a pair of rollers with the adjustable plates spanning the space between them (shown in Fig. 1) and bearing upon the surface thereof 55 while the rollers are in motion, thus providing means whereby the rollers may be leveled to correspond with one another without stopping the mill for this purpose, and such training or leveling of the rollers gives better results than if the mill were brought to a standstill.

In testing the rollers the operator, after placing my device in position, can readily discover whether either end of the rollers is 65 higher than the opposite roller, and if such be the case it is immediately detected by the operator in that the wheel or disk revolves, because under such circumstances only one roller engages the wheel A. The false end of 70 the roller may then be raised or lowered, as the case may be, thus bringing the two rollers parallel with one another, and should the test prove that both rollers are running true and are perfectly parallel to one another the wheel 75 or disk remains stationary.

Having thus described my invention, what I claim, and desire to secure by Letters Patent, is—

1. A testing device for grinding-rollers, 80 whereby the rollers are detected when out of alinement, consisting of the horizontally-revoluble disk or wheel and a gage-bar arranged below said wheel, the wheel adapted to be laid upon the rollers, with the gage-bar between 85 them, for the purpose specified.

2. A detector applicable to grinding-mills, whereby the non-alinement of the rollers may be detected, consisting of a portable disk, 90 loosely arranged upon a vertical axle, a handle for the axle and a gage secured to said axle below the disk and adjustable plates arranged at right angles to said disk, and the latter as well as the former adapted to bear upon the surfaces of the rollers, all substantially as described.

3. In a gage for roller grinding-mills, the combination of a wheel provided with a central opening, a stem journaled in the opening and formed with a handle on its upper end, 100 a cross-bar, on the lower end of the stem, having its ends bent downward at right angles, plates i, formed with slots h on the bent ends of the cross-bar, and clamping-screws through

the parts to hold the said ends and the plates together, substantially as described.

4. In a device for gaging the rollers of grinding-mills, the within-described gage and testing device, comprising the horizontally-revolving disk journaled on the stem of the handle, the latter having a shoulder, the transverse bar secured to the stem, and provided with bent ends and the plates adjustably at-

tached to these ends and held in position by the thumb-screws, all substantially as described.

In testimony whereof I have affixed my signature in presence of two witnesses.

DOUGLAS M. CAREY.
